KNITTING METHOD AND MACHINE

Harold E. Houseman, Laconia, N. H., assignor to
 Scott and Williams, Incorporated, Laconia,
 N. H., a corporation of Massachusetts

Application November 1, 1940, Serial No. 363,822

19 Claims. (Cl. 66—135)

This invention relates to a knitting method and machine, and particularly to a knitting method and machine adapted for the production of wrapping in a broad rib fabric.

In the application of James L. Getaz, Serial No. 340,292, filed June 13, 1940, there is disclosed a circular knitting machine of the double cylinder type provided with means for wrapping one or more selected needles for the production of designs. In accordance with the disclosure of said Getaz application, wrapping on one or more needles is effected by the selective raising of needles to take a wrap yarn as the yarn is projected outwardly and temporarily restrained from free movement with the needles by means of a relatively stationary engaging element. If the mechanism such as described in the Getaz patent is not adjusted to a high degree of accuracy, the wrapping may not be properly effected for several reasons. First, the needles which pass at the low non-wrapping level are likely to engage the wrap yarn if that yarn happens to have a relatively slight amount of slack. Secondly, the wrap yarn under the same circumstances may possibly engage the raised needles below their latches, whereby it would not be knit. Third, if the wrap yarn is accidentally located too low on the raised needles, it is likely to be pushed outwardly to such extent that it may drop in front of the needles in non-wrapping positions as the needles are brought together for the conventional knitting wave, and it may accidentally be knit thereby.

These difficulties in the way of panel wrapping have been solved in ordinary single cylinder machines by having inside the needle cylinder an arcuate wrap yarn supporting arm which, in the case of a rotating cylinder machine, will remain stationary. When the wrap yarn is swung outwardly, it is swung over this arm, which insures that it remains so high as to be definitely above the latch of any needle which is to be wrapped as well as above the level of the hooks of any needles which are not to be wrapped, and also insures its being well up in the hook of the needle, so that as the wrap needles join the unwrapped needles, the wrap will lie inside the unwrapped needles so as not to be taken thereby. This supporting element or arm terminates prior to the point where the wrap yarns are drawn into loops along with the main yarn. By carefully locating the end of the supporting element with respect to the knitting point, the take-ups on the wrap yarns will have time to absorb most of the excess yarn formed into a loop by the supporting element. It is generally best to have the take-up fail to eliminate all of the loop, as a little slack in the wrap yarn as it is drawn over the sinkers causes it to lie loosely on the loops of main yarn to plate better by providing better coverage. Varying the tension of a take-up spring will

cause the take-up to act faster or slower. Thus the supporting element also plays a part in securing the most satisfactory plating by the wrap yarn.

5 The use of such an element in wrapping is disclosed in the patent to Taggart 2,025,913, dated December 31, 1935.

In a machine of single cylinder type, as disclosed in the Taggart patent, the mounting of this supporting arm or element is a simple matter, because it can be carried by the latch ring through the medium of a bridging element extending across the circle of needles.

10 In the case of a superposed cylinder type of machine, such mounting of the supporting element is impossible, inasmuch as the upper and lower cylinders, together with the needles which move across their approaching ends, form a rotating cage into which no stationary elements may extend. The mountings and operation of the wrap fingers, furthermore, preclude extending downwardly through the upper cylinder any stationary means for the purpose of mounting the wrap yarn supporting element.

15 20 It is the object of the present invention to provide means for the mounting of such wrap yarn supporting element, which may be conveniently referred to as a "horn," since in the superposed cylinder type of machine it most desirably assumes such a form consistent with assembly with other elements. The operation of the horn requires that it be at least substantially stationary (in a rotating cylinder machine) at a time following the projection of a wrap yarn over it, and

25 30 35 40 45 It is the object of the present invention to provide means for the mounting of such wrap yarn supporting element, which may be conveniently referred to as a "horn," since in the superposed cylinder type of machine it most desirably assumes such a form consistent with assembly with other elements. The operation of the horn requires that it be at least substantially stationary (in a rotating cylinder machine) at a time following the projection of a wrap yarn over it, and according to the present invention, such relatively stationary condition of the horn is secured in either of two alternative fashions. In one case, it normally partakes of the rotation of the cylinders, but is caused to be temporarily stationary, or substantially so, at the time it is cooperating with a wrap yarn. In an alternative embodiment of the invention, it is actually maintained stationary at all times by the use of an epicyclic gear train arrangement which transfers through rotating elements to the horn the stationary status of an element which may be located above the upper cylinder without interference with the rotating parts of the mechanism. The general object indicated above, as well as specific objects relating to details of accomplishment of the main object, will become apparent from the following description, read in conjunction with the accompanying drawings, in which:

the same machine illustrating the operating means for the horn;

Figure 3 is a horizontal section showing the verge of the machine and its associated parts;

Figure 4 is a fragmentary elevation of the matter of Figure 3;

Figure 5 is a perspective diagrammatic view further illustrating the fashion in which the yarn is manipulated in the production of wrapping;

Figure 6 is an axial section through an upper cylinder and its associated parts illustrating a modified embodiment of the invention;

Figure 7 is a horizontal sectional view showing in plan the means for maintaining the horn stationary and for securing its fine adjustment; and

Figure 8 is a horizontal sectional view through the lower portion of Figure 6 illustrating the verge and the internal gear associated therewith.

Referring first to the embodiment of Figures 1 to 5, inclusive, this illustrates the device for temporarily securing a substantially stationary condition of a wrap yarn supporting horn which is generally moving with the needle cylinders. The lower and upper cylinders of the machine are illustrated respectively at 2 and 4 and are provided with slots in the usual fashion for the reception of the double ended needles 6 which are controlled by jacks 8 slideable in the lower cylinder and which cooperate with conventional sinkers 10. The knitting mechanism is conventional and reference may be made to the above mentioned Getaz application for preferred details thereof.

Within the upper cylinder, and arranged to rotate with it, is located a verge 12, provided with openings 14 through which are adapted to project the wrap yarn carrying fingers 16 to project their wrap yarns 18 into position to be taken by selectively raised needles. The wrap yarn is projected sufficiently far outwardly to engage a relatively stationary member 20, which retards its movement and thereby effects its seizure by the hooks of the selectively raised needles. All of the elements so far described operate as fully set forth in said Getaz application.

In accordance with the present invention, however, the wrap yarns are projected over a horn 22, which serves to determine the level of the wrap yarn and provide slack therein for the purposes set forth in the introduction. The fashion in which the yarn is moved is illustrated most clearly in Figure 5, in which it will be noted that at the time the yarn is being retarded or spread to engage the hooks of the needles, it extends about the horn 22. Shortly after its engagement with the needles is completed, however, it should be released by the horn. If the horn was stationary as the cylinders revolved, it would be obvious that this would occur by the slipping of the wrap yarn off the right hand end of the horn as viewed in Figure 5.

To effect such relative retardation of the horn with respect to the cylinders, the horn is carried by a slide 26 mounted by means of screws 30 passing through elongated slots 28 so as to have an oscillatory motion about the axis of the cylinders. Engaging an opening 32 in the slide 26 is the end 34 of a lever 36 pivoted at 38 on the verge and urged in a counter-clockwise direction, as viewed in Figure 3, by a spring 40. The lever 36 carries a sloping cam 42 which is arranged to be engaged by a push rod or plunger 44 mounted in slots in the lower and upper wrap finger guide members 46 and 48, respectively, held in position by spring bands 50 and 52, and normally urged

upwardly to a position limited by a stop 56 by means of a tension spring 54. The various elements just described are supplied for each of the horns, one of which is located at each of the positions where wrapping is to take place. Two of such positions are illustrated in the drawings.

Arranged to cooperate with the plungers 44 is a cam 58 carried by a lever 60 mounted in a bracket forming a portion of the frame 17. The lever 60 is preferably carried by a shaft 62 so that the cam 58 may be moved into and out of operative position by connections from the main cam drum of the machine. The cam is desirably out of operative position during the periods in which no wrapping is taking place.

The operation of this arrangement will be apparent from the foregoing description. Normally, each horn 22 occupies a position such as illustrated in Figure 5, i. e., projecting completely across the opening through which the wrap yarn carrying finger or fingers are projected. (In general, a plurality of these fingers carrying different color yarns will be provided, though only one is illustrated at each wrap position in the drawings.) The wrap yarn normally extends from the last loop in which it is knit about the outer edge of the verge and over the rounded portion 24 of the verge directly beneath the horn 22 to its carrying finger 16. When the position is approached for the projection of the wrap yarn to engage it with the selectively raised needles, the wrap yarn finger 16 moves outwardly, drawing the yarn over the horn 22 into position to be engaged by the arresting member 20, whereby it is spread to be engaged by the needles. Up to this time, the horn 22 occupies its original position, but soon after the spreading is completed, the plunger 44 will engage cam 58, thereby being forced downwardly and, by the action upon the cam 42, causing the lever 36 and the corresponding slide 26 to move rearwardly relative to the direction of rotation of the cylinders. As a result of this, the horn moves sharply to the left as viewed in Figure 5 relative to the needle cylinders and so clears the wrap yarn, being moved by the action just described to a sufficient extent to insure complete clearance of the wrap yarn, irrespective of the extent of the wrapping which has taken place. As soon as the cam 58 is cleared, the spring 40 may snap the slide 26 and horn 22 in a forward direction to its initial position. In such movement, since the arresting element 20 will have released the yarn, and since at this time the wrap yarn finger 16 will have been withdrawn, the yarn will extend directly from the last needle it engaged, which will by this time have been lowered below the horn, across the portion 24 of the verge, so that the horn will move outside it. The end of the horn is preferably provided with a rounded point as illustrated to insure that it will pass outside the yarn.

While the momentary stationary condition of the horn has been referred to, it will be evident that this is merely a relative condition and that the horn need not have imparted to it a retarding motion relative to the needle cylinder equal to the forward rate of movement of the cylinder, so that it would appear to an outside observer momentarily stationary. To such observer it may well appear to move continuously forwardly but momentarily at a somewhat slower rate than the needle cylinder, or even momentarily backwards. All that is important is to have it release the warp yarn at the proper time and then be restored to its original position by the

spring 40 after the wrap finger retarding element 20 and the needles have so moved that the yarn will be in a position for the horn to move over and outside it. Where, therefore, reference is made to a temporary relatively stationary condition of the horn, it is to be understood that there is meant only a retardation of its forward movement in such fashion as to secure the aforementioned results. Further it will be evident that the invention is applicable to a stationary cylinder type of machine, in which case the horn will have a momentary reciprocation, being normally stationary with the cylinders.

In the modification of Figures 6, 7 and 8, a horn is actually maintained in stationary position so that its action is substantially identically that of the wrap yarn supporting element described in the Taggart patent. In this modification, the upper needle cylinder is illustrated at 10, a double ended needle at 12 and a sinker at 14, the two latter elements being supported in the lower needle cylinder, which is not illustrated. A verge 16 is carried by a spindle 18 and rotates with the upper needle cylinder. The verge in this case is provided with an arm 22 and 15 otherwise is of more or less skeleton form, provided with upwardly extending lugs 24 provided with steps on which rests the internal gear 26 carrying the horn 27. Above the internal gear 26, and holding it in position, is a ring 28, secured to the verge by means of screws and keyed as indicated at 30 to the cylinder 10.

A pinion 32 meshes with the gear 26 and is carried by an upright shaft 32 mounted in the arm 22 and a bearing lug 34 carried by the plate 36, which is secured by screws 38 to the upper ring gear 40, which is in turn secured to the upper cylinder by screws 42. At its upper end, the shaft 32 carries a pinion 44, which meshes with the internal teeth of a plate 46 held concentric, and in flatwise engagement, with the plate 36 by keying members 48. The plate 46 is provided with a leg 50 adjustable between clamping screws 52 threaded through lugs in the machine frame. By this arrangement, as 45 will be evident hereafter, a fine adjustment may be imparted to the plate 46 and in turn transferred to the horn 27.

The lower wrap finger supporting disc 114 is secured to a sleeve 116 and provided with a slot 55 50 55 through which the shaft 32 normally passes, which slot is sufficiently large to clear the bearing 34 and the upper pinion 44 when the sleeve 116 is raised to lift the wrap yarn fingers 16 to threading position, as described in said Getaz application. The pin 120 normally locks the member 114 to the verge.

It will be evident from the description of this modification that the horn 27 occupies a stationary position during the rotation of the cylinders and the elements carried thereby, since the pitch diameters of the internal gears 26 and 46 are the same, as are also the pitch diameters of the pinions 32 and 44. As the cylinders rotate, the pinions and their shaft 32 rotate bodily with them, but the rotation of the shaft 32 is so related automatically to the rotation of the cylinders that the gear 26 remains stationary. The horn 27 is located at the wrapping position in such fashion as to have the wrap yarns laid thereover and then clear its end at the proper time, so that it functions the same as the wrap yarn supporting or guiding element of said Taggart patent. The position of the horn 27 may be adjusted by the screws 52, since it will be evi- 70 75

dent that any adjustment imparted to the plate 46 will be precisely reproduced in the gear 26.

The mounting and operation of element 20, which forms no part of the present invention, is indicated in Figures 3 and 6. It is mounted upon a pivot 131 and is provided with a pin 130 engaged in a slot in an arm 128 carried by a vertical rod 128, which is pulled downwardly by a spring 132 into engagement with a cam (not shown) on the cam drum of the machine. At its upper end, the rod 128 carries an arm 126, provided with a cam-following pin 133 urged into engagement with cams 134 on the rotating plate 106 by means of a spring 125. An abutment screw 127 limits the outward movement of the arm 126 under the action of the spring.

In the operation of the machine, when the element 20 is not operating, i. e., when wrapping is not taking place, the plunger 128 is raised by a drum cam so that the follower pin 133 is not engaged by the cams 134. Under such circumstances, therefore, the element 20 is withdrawn from the vicinity of the needle circle. On the other hand, when wrapping is taking place, the plunger 128 is released for downward movement under the action of spring 132, and upon the approach of each of the wrap fingers or groups thereof to the location of the element 20 cams 134 will act upon the pin 133, serving to move the element inwardly to engage the wrap yarn and properly present the same to the needles. The cams 134 are so designed as to impart to the element 20 the necessary inward movements to insure entry of the yarns into the hooks of the elevated needles which are to take them.

While the invention has been particularly described with reference to panel wrapping, it will be evident that the invention is equally applicable to individual needle wrapping in which there is never any wrapping of more than one needle by a single yarn finger in any one course. In such case, the horn has the useful function of insuring that the yarn is maintained at a quite definite height on the needle to be wrapped so as to wrap it properly and avoid engagement with any adjacent needle.

What I claim and desire to protect by Letters Patent is:

1. A circular knitting machine of the superposed cylinder type comprising upper and lower cylinders, needles arranged to slide in said cylinders, wrap yarn feeding means, an element arranged to support wrap yarn in the wrapping operation, said element extending in a circumferential direction inside the circle of needles, and means for effecting relative movement between said element and the needle cylinders at least at the time of the wrapping operation.

2. A circular knitting machine of the superposed cylinder type comprising rotating upper and lower cylinders, needles arranged to slide in said cylinders, wrap yarn feeding means, an element arranged to support wrap yarn in the wrapping operation, said element extending in a circumferential direction inside the circle of needles, and means for effecting relative movement between said element and the needle cylinders at least at the time of the wrapping operation, the last named means comprising elements located within, and rotating with, the upper cylinder.

3. A circular knitting machine of the superposed cylinder type comprising rotating upper and lower cylinders, needles arranged to slide in said cylinders, wrap yarn feeding means, an ele-

ment arranged to support wrap yarn in the wrapping operation, said element extending in a circumferential direction inside the circle of needles, and means for maintaining said element substantially stationary during at least a portion of the rotation of the needle cylinders.

4. A circular knitting machine of the superposed cylinder type comprising rotating upper and lower cylinders, needles arranged to slide in said cylinders, wrap yarn feeding means, an element arranged to support wrap yarn in the wrapping operation, said element extending in a circumferential direction inside the circle of needles, and means for imparting to said element motion relative to said needle cylinders during their rotation.

5. A circular knitting machine of the superposed cylinder type comprising rotating upper and lower cylinders, needles arranged to slide in said cylinders, wrap yarn feeding means, an element arranged to support wrap yarn in the wrapping operation, said element extending in a circumferential direction inside the circle of needles, and means for imparting to said element a backward and then a forward movement relative to said needle cylinders during their rotation.

6. A circular knitting machine comprising a circular rotating series of needles, wrap yarn feeding means, an element inside the needle circle arranged to support wrap yarn in the wrapping operation, and means for effecting general circumferential movement of said element through complete revolutions with the needles but for effecting movement relative to the needles at predetermined times.

7. A circular knitting machine comprising a circular series of needles, wrap yarn feeding means, an element inside the needle circle arranged to support wrap yarn in the wrapping operation, an abutment for engaging the yarn between the wrap yarn feeding means and said element, and means for withdrawing said element circumferentially from yarn supporting position before the drawing of loops.

8. A circular knitting machine comprising a circular rotating series of needles, wrap yarn feeding means, an element inside the needle circle arranged to support wrap yarn in the wrapping operation, and means for causing said element to revolve with needles while wrapping is taking place and for subsequently arresting said movement to free the wrap yarn.

9. A circular knitting machine comprising a circular rotating series of needles, wrap yarn feeding means, an element inside the needle circle arranged to support wrap yarn in the wrapping operation, and means for both rotating said element and for oscillating it circumferentially with respect to the needles during each revolution of the needles.

10. The method of wrapping a yarn about selected needles which comprises passing the yarn over a supporting element inside the needle circle and about the needles at a time when there is no relative movement between said supporting element and the needles and subsequently moving the supporting element with respect to the needles to free the wrap yarn from said element.

11. A circular knitting machine of the superposed cylinder type comprising upper and lower cylinders, needles arranged to slide in said cylinders, wrap yarn feeding means, an element arranged to support wrap yarn in the wrapping operation, said element extending in a circum-

ferential direction inside the circle of needles, and means for effecting relative movement between said element and the needle cylinders at least at the time of the wrapping operation, the last named means comprising an epicyclic gear train extending within the upper cylinder.

12. A circular knitting machine of the superposed cylinder type comprising upper and lower cylinders, needles arranged to slide in said cylinders, wrap yarn feeding means, an element arranged to support wrap yarn in the wrapping operation, said element extending in a circumferential direction inside the circle of needles, and means for effecting relative movement between said element and the needle cylinders at least at the time of the wrapping operation, the last named means comprising a plunger extending within the upper cylinder and rotating therewith.

13. A circular knitting machine of the superposed cylinder type comprising upper and lower cylinders, needles arranged to slide in said cylinders, wrap yarn feeding means, an element arranged to support wrap yarn in the wrapping operation, said element extending in a circumferential direction inside the circle of needles, and means within the upper cylinder for effecting relative movement between said element and the needle cylinders at least at the time of the wrapping operation.

14. A circular knitting machine of the superposed cylinder type comprising upper and lower cylinders, needles arranged to slide in said cylinders, wrap yarn feeding means, and an element inside the needle circle for supporting wrap yarn.

15. A circular knitting machine of the superposed cylinder type comprising rotating upper and lower cylinders, needles arranged to slide in said cylinders, wrap yarn feeding means, and a substantially stationary element inside the needle circle for supporting wrap yarn.

16. A circular knitting machine of the superposed cylinder type comprising rotating upper and lower cylinders, needles arranged to slide in said cylinders, wrap yarn feeding means arranged to project wrap yarn across the needle circle, and an element arranged to engage a wrap yarn between the point at which it was last knit and the part thereof to be engaged by a needle to control the position of the portion thereof extending across the needle circle.

17. A circular knitting machine of the superposed cylinder type comprising rotating upper and lower cylinders, needles arranged to slide in said cylinders, wrap yarn feeding means, and means within the needle circle for engaging a wrap yarn to insure its location across the needle circle at a level above the latch of a needle moving to engage it.

18. A circular knitting machine of the superposed cylinder type comprising upper and lower cylinders, needles arranged to slide in said cylinders, wrap yarn feeding means, and an element inside the needle circle for supporting wrap yarn prior to drawing loops thereof into the fabric.

19. A circular knitting machine of the superposed cylinder type comprising rotating upper and lower cylinders, needles arranged to slide in said cylinders, wrap yarn feeding means, and a substantially stationary element inside the needle circle for supporting wrap yarn prior to drawing loops thereof into the fabric.
